UNITED STATES PATENT OFFICE.

LEWIS W. ROE AND LEWIS J. BONAR, OF MANSFIELD, OHIO.

PIPE-CLEANER.

No. 853,428.

Specification of Letters Patent.

Patented May 14, 1907.

Application filed March 16, 1907. Serial No. 362,648.

To all whom it may concern:

Be it known that we, LEWIS W. ROE and LEWIS J. BONAR, citizens of the United States, residing in Mansfield, county of Rich-
5 land, and State of Ohio, have invented a new and useful Improvement in Pipe-Cleaners, of which the following is a specification.

The object of our invention is to provide a device adapted to ream out and clean from
10 the bowl of a pipe the substance commonly called "cake."

A further object is to construct such a device in a simple, strong, durable and inexpensive, manner.

15 Another object is to construct such a device adapted to serve the dual purpose of a pipe cleaner and a key ring.

Our invention consists of certain details of construction hereinafter set forth pointed
20 out in our claims and illustrated in the accompanying drawings in which

Figure I shows a side elevation view of our device, Fig. II shows an edge elevation view of the same, and Fig. III shows a transverse
25 sectional view taken on the line 3—3.

Referring to the accompanying drawings the reference numeral 10 is used to indicate one portion of our device which is shaped similar to one portion of an ordinary set of
30 pliers except that at the base of the jaw we have mounted an inwardly extending lug 11 provided with an orifice centrally located. The handle part 12 of said portion 10 is, by construction, curved inwardly assuming the
35 shape of a semi-circle and the outer end of the jaw portion 13 is curved inwardly at 14, said curve being designed to conform, in combination with a like and companion curve 15 on the jaw 16 of the companion portion 17
40 hereinafter described, to the curve at the base of a pipe bowl. The numeral 18 indicates a raised part extending longitudinally along the upper surface of the jaw 13 said part being provided with cutting edges for
45 purposes hereinafter set forth.

The numeral 17 indicates a portion de-

signed as a companion to the portion 10, said portion 17 being provided with an inwardly extending lug 19 containing an orifice centrally located, said lug being designed to engage the lug 11 when the two portions of our device are joined. The handle part 20 of the portion 17 is curved inwardly and designed to overlap the handle part of the portion 10, the two portions thus overlapping forming a 55 ring which is adapted for holding keys or other like articles.

The numeral 16 indicates the jaw part of the portion 17 which is curved at its outer extremity as hereinbefore described and the 60 numeral 21 indicates a longitudinally extending and centrally located raised part on the outer surface of the jaw 16 said raised part being exactly similar in every respect to the raised part 18.

65 The numeral 22 indicates the rivet connecting the two parts.

In practical use the device is inserted in the bowl of a pipe and inward pressure applied to the handles. The device is then 70 turned in the pipe bowl and the cutting edges on the raised portions engaging the cake the same is reamed out and the bowl cleaned.

Having thus described our invention what we claim and desire to secure by Letters Patent of the United States, is:

A pipe cleaner comprising in combination two portions movably secured to each other in such a manner as to cause the jaws to move outwardly when pressure is applied to 80 the handles; a raised portion, provided with a cutting edge, mounted on each jaw; jaws curved at their outer extremities to conform to the curve in the base of the pipe bowl; handles overlapping each other and designed to 85 form a ring, all arranged and combined substantially as shown and described.

LEWIS W. ROE.

LEWIS J. BONAR.
